UNITED STATES PATENT OFFICE

ALBANO SCHMALZ, OF CHICAGO, ILLINOIS

DRILL ROD

Application filed December 12, 1927. Serial No. 239,416.

My invention relates in general to well drilling tools.

It relates more particularly to a drill and a device adapted to be used in connection therewith by means of which the drill may be withdrawn in a single piece from the shaft should any part thereof become broken.

In the drilling of deep wells such as oil wells running as deep as five thousand feet in extreme cases, the equipment employed comprises a drill rod in the form of jointed sections of hollow casing with a suitable style of bit, the bit being so formed that the product of the drilling, earth, stones or the like, progresses upwardly through the casing where it is discharged out of the top thereof. These casings are apt to break where they are joined together or the threads may strip and in either event, when the drill is withdrawn, part of it will remain in the bottom of the well. The portion remaining in the well must be removed by a fishing operation. This is always a tedious and difficult operation and very often an impossible one, so that there are a great many wells almost completed which are entirely worthless due to the presence of broken tools at the bottom thereof.

Suggestions have been made for fastening the sections of casing together by an auxiliary coupling of some kind on the inside thereof, so that if the casing shell should break, the drill rod would still hold together sufficiently to permit it to be withdrawn in a single piece. The mechanisms suggested for this purpose are entirely unfitted for practical use with deep wells such as those usually drilled for oil, and furthermore they have the disadvantage of interfering with the efficient and easy operation of the drilling tools. They are hard to assemble and for this reason have not met with any success in practical use.

The principal object of my invention is to provide improved means for recovering well drilling tools.

Another object is to provide a safety device for interconnecting the casings which will be connected at the same time that the casings are connected and in a single operation.

Another object is to provide such a connec-

tion adapted to swivel at each casing joint.

Another object is to provide such an instrumentality adapted to swivel at each casing joint when turned in one direction, but adapted to hold itself against turning when the casing is turned in the opposite direction.

Another object is to provide connections on the inside of the casings which will be interconnected with the act of coupling the casings, and disconnected in the same way.

Another object is to provide improvement in bits particularly adapted for use with my improved drilling mechanism.

Another object is to provide a drilling tool with connected links of cable extending the full length of the casings, each section of cable being of substantially the same length as each section of casing.

Another object is to provide a drilling tool in the form of sections of casing with sections of cable held in each casing, the cables being adapted to be jointed together when the casings are coupled together.

Other objects and features of my invention will be apparent from the following detailed description taken with the accompanying drawings, wherein

Fig. 1 is an elevational view of one form of my invention, partly in section to show the relationship of the parts;

Fig. 2 is an enlarged vertical sectional view of part of Fig. 1, the midportion of the figure being broken away to conserve space;

Fig. 3 is a plan sectional view along the line 3—3 of Fig. 2;

Fig. 4 is a similar view taken along the line 4—4 of Fig. 2;

Fig. 5 is a bottom view showing the arrangement of the bit;

Fig. 6 is a vertical sectional view showing a modification of the invention;

Fig. 7 is a plan view of the embodiment of Fig. 6, and

Fig. 8 is a sectional view taken along the line 8—8 of Fig. 6.

Referring now to the drawings wherein like reference characters are employed to designate similar members throughout the several views, the invention is adapted to be applied to the usual form of casings 10 se-

cured together by couplings 11 having an integral spacing ring 11a. It is on the inside of the standard casings that the safety cable is secured. In the more elaborate form, the 5 cable is protected by a sheath or tube, and this form as shown in Figs. 1 to 5 inclusive, will now be described.

A length of standard left hand cable 12 is employed and has an upper head 13 secured 10 thereto, preferably by an arrangement such as that shown wherein the head is hollow to receive the cable and has an upper bevelled portion 14 to which the cable is drawn, an expanding pin 16 being driven into the top 15 of the cable as shown, to enlarge the top thereof and fill up the enlarged core of the head 13 in the manner shown. The top of the core is then stopped with any suitable solder or the like and finished smooth and flat. The 20 cable is protected by a sheath or tube 17 and at the top thereof is a flanged collar 18 provided with a leather washer 19, a metal washer 21, and a hexagon nut 22 which is threaded onto the outer threads on the head 25 13. The head is provided with flats 13' to accommodate a wrench during this operation.

At the bottom of the cable, a swivel head 23 is secured by an expanding pin 24 and is adapted to bear against an interior shoulder 30 on a swivel member 26, this member being of hexagonal shape on the outside to prevent its turning and extending into an interior hexagon shaped socket in a bottom tube cap 27. The cap 27 is held onto the tube by friction 35 and has a centrally apertured cross piece 27a through which the cable extends, a compression spring 28 being disposed between the cross piece and an annular groove in the enlarged end of the swivel member 26. The 40 swivel member is interiorly threaded to receive a plug 29 and a packing nut 31 secured to a depending thread portion, and the bottom tube cap 27 is adapted to contain a packing material 32 for preventing foreign matter 45 from coming in contact with the swivel. The plug 29 is of course adapted for the same purpose.

In order to space the tube and support it in the casing, top and bottom spacing supports 33 and 34 are provided, the top spacing support being shown in the form of a spider, while the bottom spacer is in the form of a split ring. In both cases an expanding nut and bolt 36 are provided to expand the 50 support against the inside of the casing to lock the entire assembly in position. The supports have openings 33' or 34' respectively, for permitting passage of material through the casing.

55 The safety cable assembly is prevented from moving with respect to the casing because the top support bears up against the collar 18 and the bottom support bears against the bottom tube cap 27. As shown in Fig. 4, this tube cap is provided with hex-

agonal sides and is adapted to extend in between two opposing straight edges on inner projections of the ring 34. This arrangement prevents any longitudinal movement of the cable assembly and also prevents turning 70 of the cable tube or sheath.

In assembling the apparatus, a cable of the proper length is cut; the bottom tube cap 27, swivel socket 26 and spring 28 are threaded thereon and the top head 13 and swivel head 23 are then secured onto the cable. The cable is then drawn through the tube 17 with the head 13 extended through first, and the bottom tube cap 27 forced into position on the end of the tube. The supports 33 and 34 are then placed around the tube, the collar 18 placed in position followed by the washers 19 and 21, and finally the nut 22. As the nut is turned up tight, care is taken that the hexagon upper outside surface of the swivel socket 26 is engaged in the hexagon socket in the bottom tube cap. The nut 22 is tightened until the cable is just taut, but not sufficiently to take up all of the play in the spring 28. The packing nut and plug are then applied around the swivel joint and the cable assembly then placed in the casing.

The cable assembly is proportioned so that it has substantially the same over-all length as the single casing section plus half a coupling including the spacing link 112. The assembled safety mechanism is placed in the casing section with the cable head 13 upwardly. The supports 33 and 34 are then placed in position against the collar 18 and cap 27 respectively, and the bolts 36 turn to expand the supports tightly against the inside of the casing.

When a safety cable has been placed in each one of the casing sections, these sections may be handled just as if there were no added mechanism, since the cables are joined together by the same act of joining the sections together. The spring 28 allows sufficient end movement of the socket 26 which of course also acts as a coupling, that is when the threaded end of the head 13 engages therein, that it will adjust itself to the travel of the head, this head of course being stationary, and the member 26 tending to move in all respects with the casing, being secured to the top of the drill. The socket 26 in other words, moves in such a way as to compensate for any possible differences in the threads on the casing and coupling on the one hand, and the head 13 and interior of the socket 26 on the other hand.

In connection with my improved drill, I have provided an improved form of bit including a head 37 having interior threads adapted to engage the lower outside threads on the casing 10 and a central exteriorly threaded projections 38 adapted to engage on the inside of the socket 26 so as to connect the cable with the head. A knife 39 is pro-

vided separate from the head but secured thereto by cap screws 41—41 extending through oppositely disposed downward projections 42 from the head. Opposite each 5 projection is an opening 43 leading vertically through the head to the interior of the lowermost casing. The lower part of the knife supporting projections is bevelled as at 42a so that there would be no possibility 10 of any obstruction such as a stone bearing against a blunt end of such projection and holding the knife out of engagement with the bottom of the shaft.

The embodiment shown in Figs. 6 to 8 inclusive, is the same in principle as that shown in the preceding figures but it is considerably simplified, the parts employed however being substantially the same as those used in the preceding arrangement. The casing 10 and coupling 11 are the same except that the coupling may be provided with interior threads 11b to receive the support 133 which is threaded onto the head 13 instead of being supported below the same as in the previously 25 described embodiment. The outside of the support, which is in the form of a spider, is also threaded and the whole support is turned onto the threads 11b as shown. The same species of expanding nut 136 is employed however, with this arrangement. It will be noted that this form has no protecting tube or sheath for the cable and the arrangement at the bottom thereof is accordingly 30 slightly different. The support 134 which is in ring form is provided with a central opening with a shoulder 134a against which an annular flange on a collar 146 is adapted to bear, the collar extending around the cable 12 in the manner shown. The support 134 is threaded onto the inside of the casing, the usual threads simply being extended a short distance to accommodate this support. It is expanded in the proper 45 position by the expanding nut and bolt 136.

Instead of the spring 28 bearing against a cross piece supported against the end of the tube, it bears against the collar 146, the swivel socket 126 being substantially the same as in the prior arrangement with the 50 exception that no provision is made for packing. The plug 29 is employed if desired, to protect the swivel to some extent, but even this may be done away with if thought desirable. In this second form, I show a modified 55 arrangement at the nut 22 in that instead of the leather washer, a single metal washer 147 is provided having an inwardly projecting portion 147a which is adapted to extend along a keyway 13a in the outside of the head, and the nut 22 applied in the usual way. This 60 nut as used in the modified form has a slot at the top thereof around which the projection 147a is shaped to be bent in the manner shown.

In assembling the modified form, the cable

with the supports 133 and 134, is placed in the casing, the nut 22 however, not being drawn up tightly. The supports are expanded in the proper position by means of the expansion bolts 126, and then the nut 22 is 70 threaded down tightly until all of the slack is taken out of the cable 12, care being taken however, that some movement remains for the spring 28, that is all of the clearance between the member 26 and the shoulder on the support 134 should not be taken up. When the nut has been turned down sufficiently, it is brought with its slot in line with the keyway 13a, and the projection 147a is then bent over in the position shown in Fig. 6. 75

Instead of assembling the unit in the manner described, in the preceding paragraph, the supports 133 and 134 if desired, may first be placed in position and expanded to keep them from turning. The remaining portion 80 of the cable assembly with the exception of the nut 122 and washer 147, is then placed in position, the head being inserted first through the axial opening in the support 134, and then extended through the opening in the 85 spider support 133. The washer and nut are then placed around the head and drawn up tightly as in the previous arrangement.

In employing the device of my invention, either one of the forms operates in exactly the 90 same way. All that is necessary is to simply place the casings in position as they are needed and screw them down in the usual manner. The coupling and casing threads engage first and then the threads on the cable 95 connecting members. These members have their edges chamfered in the manner shown to facilitate engagement of the threads.

While each casing section has its own cable, each one of these cables has its own swivel 100 so that if for any reason whatsoever a casing section should turn and the next lower casing fail to turn, the cable turns on its swivel and thus avoiding any possibility of twisting off independent of how long the turning of the 105 casing continued. This function would take place whether the casing itself were broken, or if the threads thereon should be stripped as usually happens when a breakdown of this kind occurs.

In spite of the fact that the cables are connected with the connecting of the casings and also have the swivels which turn when occasion demands, the cable is so arranged 110 that it will be held absolutely stationary 115 when the casing is turned in a reverse direction, and so there will be no difficulty in separating the cable sections as an incident to the uncoupling of the casing sections. As the drawings show, the cable is twisted in a 120 left hand direction or what is sometimes termed a right lay cable so that any tendency to turn the same in a left hand direction has the effect of shortening it. If the cable 125 starts to turn as a casing is being removed, 130

it will quickly start to shorten and finally the head 13 will be maintained in an absolutely stationary position, due to the shortening of the cable, and the concomitant pulling together of the two heads thereon. Both of the cables effected in the uncoupling operation are acted upon in the same way, but the swivel socket 26 is of course prevented from turning due to its engagement within the support 34.

Considerable advantage is obtained by employing the spring 28 in the manner shown. This not only serves to compensate for differences in the casing threads and cable threads, but prevents any strain being applied to the cable until such a time as it will be required to withdraw the casing i. e. when a casing breaks. This is very valuable in saving the cable connections as a continuous strain thereon might have the effect of fatiguing the metal of the threads, and certainly would cause wearing a great deal sooner than if no strain were applied thereto. Consequently the expense involved in using a device of my invention is considerably reduced.

If an indefinite life is desired for the cable, the form shown in Figs. 1 to 5 inclusive, would probably be preferred. The cable in this form can be greased thoroughly and when assembled would be entirely out of contact with water, grit, stone and the like which might deleteriously affect it. This form is slightly a disadvantage however, where the embodiment of Fig. 6 is concerned, because it would be more expensive. This latter form has the advantage of simplicity and economy. While the cable is exposed it can still be protected to a certain extent by having a suitable flexible coating of some kind applied thereto. This might be oil, wax, paint, lacquer, varnish or in fact any kind of a covering which would afford it some measure of protection.

One of the principal advantages of my invention over similar devices of the prior art, is that nothing is left to be taken care of by careless workmen. It is not necessary separately to attach the cables and this is of sufficient value that it practically makes my invention commercially operable. It is well known that the principal object in sinking a well is to operate the drill, and the use of precautions which will be valuable in an emergency is secondary. Consequently most workmen will very readily forget matters of secondary importance in their hurry to discharge duties of first importance, or at least what seems so to them. In the arrangement of my invention the workman need not consider or even think about the cable but simply operates the drill as if there were no thought whatsoever of the safety cable on the inside thereof.

It will be noted that the socket is on the

bottom of the cable and the solid head at the top. This prevents the filling of the opening in the socket with earth or stones which would have the effect of preventing the coupling together of the two cable connections. 70

If it is desired to leave the casing temporarily in the ground to pump oil therethrough, as is sometimes done when the yield is slight, this may be done with my invention the same as without it, for the oil can pass through the openings 33' and 34'.

Whereas I have described some of the features of my invention in detail to make it clear to those skilled in the art. It is obvious that I do not restrict myself to this particular form and the invention is limited only by the scope of the appended claims. 80

What I claim as new and desire to secure by United States Letters Patent is:—

1. In a well drilling tool including a plurality of coupling casings, a safety element in each casing including a flexible cable with a threaded socket at one end thereof and a threaded head at the other, means for causing said casings and respective elements to rotate together so that separate safety elements in the respective casings are interconnected and disconnected as an incident to the interconnecting and disconnecting of the casings and a swivel joint disposed between the head and socket in each safety element to prevent twisting the cable in the event of accidental breaking of a casing or stripping of the threads therebetween. 90

2. In a well drilling tool including a plurality of coupled casings, a safety element in each casing and means permitting the interconnecting and disconnecting of the safety elements as an incident to the interconnecting and disconnecting of the casings, said safety element having an interiorly threaded socket on one end and an exteriorly threaded head on the other end, the socket of one element adapted to be threaded connected to the head of the adjoining element when the two casings are coupled together, means being provided for compensating, for differences in the threads on the casing and safety element so that both may be screwed up tightly together and without strain. 100

3. In a well drilling tool including a plurality of coupled casings, a safety element in each casing, threaded coupling means on the ends of the safety element means for causing said casings and respective elements to rotate together so that safety elements are interconnected and disconnected as incident to the interconnecting and disconnecting of the casings, and means for avoiding the placing of any strain on the safety elements during normal operation of the drill. 110

4. In a well drilling tool including a tubular casing, a safety cable in the inside of the casing, a swivel joint in the cable adapted to be turned when the cable is turned in a right 120

hand direction and means preventing turning at the swivel joint in a reverse direction whereby said swivel will turn if a casing should break during a drilling, but will be held stationary when one casing section is removed from another.

5. A safety cable mechanism for use in standard oil drill casings, said mechanism including cables with mutually coacting 10 couplings at the ends thereof, and spacing supports adapted for mounting said coupled cables within said standard casing, said spacing supports including a split ring adapted to engage against the inside wall of the casing and readily operable means for expanding said ring to interengage the same with said casing wall.

6. A safety cable mechanism for use in standard oil drill casings, said mechanism 20 including cables with mutually coacting couplings at the ends thereof, and spacing supports adapted for mounting said coupled cables within said standard casing, said spacing supports including a split ring adapted 25 to engage against the inside wall of the standard casing, with apertures within the circumference of the ring to permit passage of matter through the standard casing as required in drilling, and readily operable 30 means including a threaded bolt for expanding said ring to interengage the same with said standard casing wall.

7. A safety device adapted to be secured to the inside of a standard drill casing, said device comprising a section of cable, a swivel 35 head on one end of the cable, a swivel socket for the swivel head, coupling means for the cable at each end thereof, and means for preventing the swivel head from turning with respect to its socket when the cable is turned in a left hand direction.

8. The device of claim 7 wherein said last mentioned means includes the use of a left hand cable adapted to shorten when turned 45 in a left hand direction.

9. A safety device adapted to be secured to the inside of a standard drill casing, said device comprising a section of cable, a swivel head on one end of the cable, a swivel socket 50 for the head, a collar about the cable, a spring between the collar and socket, and a threaded head at the other end of the cable, the swivel socket being interiorly threaded to receive the head of an adjoining cable device to secure 55 them together.

10. The device of claim 9 with a pair of spacing supports expandable on the inside of the casing and having axial openings for the cable, said collar engaging against one of said supports, and a nut provided on the threaded head engaging against the other support to maintain the cable taut.

11. The device of claim 9 with a pair of spacing supports expandable on the inside of the casing and having axial openings for the

cable, said collar engaging against one of said supports, and a nut provided on said threaded head engaging against the other support to maintain the cable taut, the swivel socket engaging within a portion of one of said supports to prevent turning of the same when two of the devices are interconnected.

12. The combination with a device of claim 9 of a bit having a head portion for screwing onto the outside of a casing, and a threaded central projection for engaging into one of said sockets, the head having two depending projections, with a removable knife secured to the projections, and vertical apertures opposite each projection and adjacent the knife, the spacing supports for the safety device also being apertured so that an opening exists throughout the casing and bit into the bottom of the shaft.

13. The device of claim 9 with means for protecting the swivel and cable to prevent foreign matter coming in contact therewith.

14. A safety device adapted to be secured to the inside of a standard drill casing, said device comprising a tube, a cable on the inside of the tube, a tube cap with a cross piece and a central aperture through the cross piece through which the cable extends, a swivel head on the end of the cable, extending into the tube cap, a threaded head on the opposite end of the cable, and a nut on the threaded head and drawn down tightly against the end of the tube to maintain the cable taut within the tube.

15. The device of claim 14 with a spring disposed between the cross piece on said tube cap and the end of the swivel socket to permit end play of said socket, said socket being interiorly threaded to be connected to the threaded head of an adjoining device, the two adjacent devices being automatically connected as the casings are coupled together, and the end play of the swivel socket functioning to compensate for minor variations in the threads.

16. The device of claim 14 wherein said tube cap is exteriorly threaded to receive a packing nut, and a plug is provided for the interior of said swivel socket to prevent the admission of foreign matter into said swivel joint.

17. A safety device adapted to be secured to the inside of a standard drill casing, said device comprising a tube, a cable on the inside of the tube, a tube cap with a cross piece and a central aperture through the cross piece through which the cable extends, a swivel head on the end of the cable, extending into the tube cap, a threaded head on the opposite end of the cable, a flanged collar extending over the tube adjacent the threaded head, a washer for excluding foreign matter disposed against the flange of said collar, and a nut on said head and drawn against the

washer for maintaining the cable taut within the tube.

18. The combination with the device of claim 17 of spacing supports with central apertures for receiving the tube, and means for expanding said supports to grip the inside of the casing, said supports engaging against said collar and said tube cap respectively, to prevent the end play of the tube and

10 cable assembly.

In witness whereof, I hereunto subscribe my name this 30th day of November, 1927.
